GEORGE M. HATHAWAY AND BENJAMIN S. TAYLOR, OF JERSEY CITY, N. J.

PERMUTATION-LOCK.

SPECIFICATION forming part of Letters Patent No. 242,199, dated May 31, 1881.

Application filed February 11, 1881. (Model.)

To all whom it may concern:

Be it known that we, GEORGE M. HATHAWAY and BENJAMIN S. TAYLOR, citizens of the United States, residing at Jersey City, in the county of Hudson and State of New Jersey, have invented certain new and useful Improvements in Permutation-Locks; and we do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

Our invention relates to a permutation-lock adapted for service in any position where a bolt and keeper may be employed in connection with such lock; and the novelty consists in the construction and arrangement of parts, as will be more fully hereinafter set forth, and specifically pointed out in the claims.

The object of the invention is to simplify the construction and improve the efficiency of permutation-locks in their adaptation for useful service in the various positions in which it may be desirable to employ them.

For convenience, we will describe the invention as applied to a trunk, chest, or other article in which the top carrying the hasp is lifted up; but it will be understood that the device is equally applicable and serviceable in other locations and relations.

In carrying out our invention we secure to the body of the trunk or stationary portion an ornamental frame, from a cross-bar of which arises a rigid keeper-hook, said frame being cut away to correspond with the ornamental conformation of the free end of the hasp. The hasp is pivoted within a frame, of similar outward appearance to the keeper-frame, and is held out of contact with the keeper, when not in a locked position, by the constant force of a spiral spring. The hasp is provided with two cavities upon the under side, one of which contains the lock mechanism, the other being adapted to receive the keeper-hook, and has an abrupt right-angled surface, which corresponds with and abuts against a similar bearing upon the keeper when the hasp is in a locked position.

Through an aperture in the hasp, upon which is formed a sleeve projecting inward, operates a shank having a rectangular extremity, upon which is secured an operating-disk having a projecting pin upon the under side, and a recess upon its periphery, having one abrupt side and an incline over which the locking-pawl rides uselessly when the shank is turned in one direction. The pin upon the under side of this operating-disk serves to rotate a series of reversible disks, having similar pins upon each side upon the same annular line, in either direction, until the three-sided recess in the periphery of each disk registers with the locking-pawl. This series of disks operates over the hasp-sleeve, and the operating-shank is secured rigidly to a semicircular plate, to which is hinged a similar plate, which is capable of being forced outward at right angles with the plane of the hasp, and serves as a handle in the manipulation of the bolt, and may be closed down upon a plane with its fellow within a circular recess in the hasp, the circular area adjacent to the edge of which is provided with proper figures or the like, adapted to guide the operator in locating the combination.

A bifurcated lug, rigid upon the under side of the hasp within the lock-chamber, embraces and holds rigidly a single spring, which is divided into several arms at one extremity, each arm being adapted to bear upon one of the series of disks and frictionally control said disk. The other extremity, being curved, bears against a shoulder upon the locking-pawl, and serves not only to control the pawl with a constant force, but also to hold the bolt in a locked position until the force is overcome by the manipulation of the shank and disks. The locking-pawl is pivoted upon an arm of the locking-bolt, and a recess in said arm receives the transverse arm of the pawl when the combination is "off."

In carrying out our invention we employ the mechanism illustrated in the accompanying drawings, which form a part of this specification, and in which—

Figure 1 is a bottom-plan view; Fig. 2, a central longitudinal section through the line x x ; Fig. 3; Fig. 3, a top-plan view; Fig. 4, a detail view of the shank and its connections detached; 100

Fig. 5, a detail view of the bolt and pawl in reversed position; Fig. 6, a detail view of the spring, and Fig. 7 a view of the operating and of one of the reversible disks.

5 Referring to the drawings, A represents the keeper-plate, ornamented or otherwise, having a recessed portion, a , which receives the free end b of the hasp B, and a cross-bar or plate, a' , from which arises a keeper-hook, A', having an abrupt side, a'' . The hasp B is pivoted at b' in a frame, B', and a spiral spring, B², socketed in the trunk-frame and bearing against the hasp, serves to hold the hasp away from the keeper when the bolt is not in operation.

10 The hasp is provided with two cavities upon the under side, one of which I will designate as the lock-chamber x , and the other as the keeper-chamber x' . The chamber x' has an abrupt or right-angled side, x'' , to correspond 15 with the similar side, a'' , of the keeper, and the continuation of this chamber in one direction furnishes the guideway in which the lock-bolt traverses.

15 Formed upon the under side of the hasp is a sleeve, C, around which operate reversible disks D, having three-sided recesses d in their peripheries, and differentially-arranged pins d' , projecting from either side of each disk. These disks are operated in either direction by 20 an operating-disk, D', having a pin, d^2 , upon the under side, upon the same annular line as the several pins d' , and also having an oblique or inclined recess, d^3 , over which the locking-pawl rides uselessly when the shank E is turned in 25 one direction. The shank E has a square or other rectangular tenon, e, upon the inner end, which fits within a corresponding aperture, e', in the center of the disk D', and the disk D' is held rigidly thereon by means of the screw 30 e^2 . The shank E operates within the sleeve C, through which it projects, and is secured upon its outer extremity rigidly upon a semicircular plate, F, hinged to which, at f, is a semicircular plate, F', which may be raised at right angles to 35 the plane of the hasp and used as a lever or knob, by which the shank and disk may be manipulated or pressed down until it rests upon a plane with its fellow, F, and both are received within a circular recess, G, formed within the 40 hasp, and the outer surface flush with the surrounding circular surface H, which is provided with figures or other designating marks, by which the operator locates the combination.

45 A bifurcated lug, I, formed upon the under side of the hasp B within the lock-chamber x , receives and rigidly embraces a flat spring, J, of steel, one extremity of which is divided into as many spring-arms j as there are reversible

disks D, which arms hold the said disks in fixed position by friction until that friction is overcome by the manipulation of the shank, and the other extremity, j' , is curved and rests against a shoulder, k, upon the locking-pawl K, pivoted at k' to the arm L of the locking-bolt L'. The pawl K has a transverse arm, K', which operates 55 in the recesses d d^3 when the combination is "on," and which recedes into a recess, l, in the arm L when the combination is "off." It will thus be observed that single spring J not only controls each disk independently, but that it 60 holds the pawl within the recesses d d^3 , and also exerts its constant force to hold the lock-bolt in locking contact with the keeper.

When the hinged semicircular plate F' is closed down the device has a very attractive 75 appearance, and leaves no projecting knob or shank end.

The device does away with many of the elements and complications heretofore employed in this art, and serves the desired purpose efficiently.

What we claim as new is—

1. The spring-hasp having lock-chamber and keeper-chamber, as shown, combined with a permutation-lock and a keeper, as and for the 85 purpose set forth.

2. The hasp B, having sleeve C, and circular recess G, surrounded by the surface H, having figures thereon, combined with the shank E, plate F, hinged plate F', and lock 90 mechanism, as set forth.

3. The combination of the disks D D', having pins d d^2 and recesses d d^3 , with the pivoted pawl K K' and bolt L', having the arm L and recess l, as and for the purposes set forth. 95

4. The single spring J, formed at one extremity into independent spring-arms j , which bear upon the disks, and the other extremity bearing against the shoulder k of the pawl, combined with the disks D, pawl K, and lock-bolt L' L l, as and for the purposes set forth.

5. The combination of the hasp B, having recess G, figured surface H, and lock-chamber x , the shank E, plate F, and hinged plate F', the disks D D', having pins and recesses, the 105 springs J, pawl K, and lock-bolt L' L l, all arranged and operating as and for the purpose set forth.

In testimony whereof we affix our signatures in presence of two witnesses.

GEORGE M. HATHAWAY.
BENJAMIN S. TAYLOR.
